APPARATUS FOR MAKING TUBULAR BODIES

Frederick Charles Wappler, New York, N. Y.

Application June 1, 1940, Serial No. 338,296

12 Claims. (Cl. 29—34)

My present invention relates to apparatus for treating a tube for the purpose of making sealed tubular bodies. Coordinately it relates to the resultant bodies themselves.

The particular type of tubular bodies toward which the present invention is primarily directed are those which are at present referred to by the medical profession as "radium seeds." These are minute elongated bodies intended for implantation in the human body for the purpose of producing certain beneficial effects upon cancerous growths and the like. Each "seed" may be composed, for example, of a small section of a gold tube having an outer diameter of perhaps three hundredths of an inch, and an inner diameter of about eight thousandths of an inch. The "seed" may be no longer than about one-eighth of an inch or so. It is tightly sealed at each end, and it contains within it a radioactive material such as radium emanations or the like.

These small bodies may be conveniently made by exposing the interior of a relatively long tube to radium emanations or the like, then sealing the ends of the tube, and subsequently severing this tube into separate sealed sections. The present invention is primarily intended to provide an improved method and apparatus for treating such a tube for the purpose of creating quantities of so-called "radium seeds" of the character mentioned.

Because of the inherently potent and dangerous nature of a tube containing radioactive material, and because of the extremely small sizes that are involved, the treatment of such a tube involves a number of unique problems which my present invention aims to solve. Moreover, in accomplishing the desired object, it is imperative, for obvious reasons, that none of the radioactive material be lost during the process of handling and treating the tube and the small sections that are produced from it. Each resultant "seed" must have ends which are reliably sealed against any escape of the radioactive material.

It has been found in practice that the mere pinching of the tube, by means of a shearing device or tool, for example, is not entirely reliable in properly sealing each resultant severed section; and that the resultant bodies have irregular and non-uniform ends which make them difficult to handle. More particularly, in creating "radium seeds," it must be borne in mind that the ultimate implantation into the human body is best effected by means of a surgical implanting instrument, and that proper handling and

control of these minute "seeds" requires that they be of uniform size and shape. Moreover, to facilitate the proper control and handling of these small bodies, whether by means of a surgical implanting instrument or otherwise, it is highly desirable that they have plane blunt ends so that they are not only of fixed length, but are capable of being maneuvered endwise in abutting relation to each other or to a plunger or the like.

These objectives, and others, are capable of achievement by means of my present invention. From a broad aspect, the present improved method of treatment consists in pinching the original tube into closed condition at spaced regions of the tube, and cutting transversely through each pinched region to produce a sealed end on each of the adjacent severed tube portions. Preferably, the pinched regions are formed successively, and the cutting operations are also performed successively and in timed relation to the pinching operations.

To achieve the desired result, I have found it to be of particular value to pinch the tube in such a manner that the resultant pinched region has a cross-section that is substantially star-shaped. This is preferably accomplished by subjecting the tube to the action of a multi-jawed chuck or collet, the jaws being at least three in number and being so shaped that when they are moved radially they will impart a substantially star-shaped cross-section to the resultant pinched region.

I have also found that the results which I seek to accomplish are best achieved by cutting transversely through the pinched regions by means of a saw, such as a rotating saw-toothed disc.

Preferably, the pinching means and cutting means are so arranged, positionally, that an intermittent endwise advancement of the tube may bring spaced regions successively to the pinching station and thereafter to the cutting station; and in carrying out my invention each advancement of the tube is preferably equal to the distance between the pinching and cutting stations, whereby both a pinching operation and a cutting operation may be performed each time the tube is at rest.

In accordance with my invention, I have devised a compact and efficient apparatus by means of which the procedural steps of the improved process may be advantageously carried out. Briefly, the apparatus involves a pinching means, a cutting means, and suitable controls for bringing about predetermined movements of the tube,

and predetermined operations, in timed relationship, of the pinching and cutting means.

The "radium seeds" which result from the practice of the present invention are, themselves, of a novel and improved character and constitute new articles of manufacture.

While I have herein described and illustrated the various features of my invention in so far as they relate to so-called "radium seeds," nevertheless it will be understood that numerous phases of my invention are not necessarily restricted to any such specific items, nor to the specific treatment of tubes intended for that purpose; and it will be recognized by those skilled in the art that a number of features of the present invention are of wider applicability, relating generally to the treatment of tubes and to the creation of sealed tubular bodies.

I achieve the foregoing objects, and such other objects as may hereinafter appear or be pointed out, in the manner illustratively exemplified in the accompanying drawings, in which:

Figure 1 is view of a typical elongated tube from which "radium seeds" may be made;

Figure 2 is a view of several sealed bodies produced from the left-hand end portion of the tube of Figure 1;

Figure 3 is an enlarged perspective view of a typical "radium seed" produced by means of the present invention;

Figure 4 is an enlarged cross-sectional view taken substantially along the line 4-4 of Figure 3;

Figure 5 is a perspective view of the present improved apparatus, with parts broken away to show elements which would otherwise be hidden;

Figure 6 is a plan view of the present apparatus, with certain parts broken away;

Figure 7 is a detail cross-sectional view taken substantially along the line 7-7 of Figure 6;

Figure 8 is a front view of the apparatus shown in Figure 6;

Figure 9 is a detail cross-sectional view taken substantially along the line 9-9 of Figure 6;

Figure 10 is an enlarged view taken substantially along the line 10-10 of Figure 9;

Figure 11 is a bottom view of the present apparatus;

Figure 12 is an enlarged longitudinal cross-section through the operating portions of the apparatus illustrating the first step in the treatment of a tube;

Figure 13 is a view similar to Figure 12 showing a subsequent step; and

Figure 14 is a view similar to Figure 13 showing a subsequent step.

Referring first to Figures 3 and 4, the sealed body 20 is of substantially cylindrical shape, constituting a section of a tube which may be, for example, of gold or the like, having an outer diameter of approximately .03 inch and an inner diameter of approximately .008 inch. The end portions of the body 20 are pinched into closed condition so that the region adjacent to each end has a substantially star-shaped configuration as indicated at 21. In the illustrated body, each region 21 has six radiating fins resulting from the squeezing action of six complementary radially-moving jaws, but it will be understood that this particular shape is shown merely by way of example and that any other similar star-shaped cross-section may be provided for. Of course, the fins must be at least three in number, resulting from the squeezing action of at least three jaws, otherwise the end of the body would have

an undesirable attenuated wedgeshape, as distinguished from the blunt end which I aim to produce.

The end surfaces of the body 20 are substantially flat and perpendicular to the axis of the tube. These blunt end surfaces impart a fixed length to the body 20 and greatly facilitate its handling and control during the process of implanting it, along with similar bodies, into the human body.

The squeezing action of the jaws, by means of which the star-shaped regions 21 are produced, usually results in extruding the fins slightly beyond the external diameter of the original tube, and that is why the ends of these fins are visible in Figure 4.

The sealed tubular body of Figure 3 is produced, by means of the present invention, from a relatively extended length of tubing 22 which has had its interior exposed to radium emanations or the like, and which has thereupon had its ends 23 and 24 pinched off or sealed in any other convenient manner to retain the radioactive material in the interior of the tubing 22. In Figure 2, the reference numeral 25 is applied to the sealed body that is first severed from the end of the tube 22. Where the pinchings 23 and 24 are of the ordinary attenuated character, as shown in Figures 1 and 2, the body 25 is not of the character shown in Figures 3 and 4. The subsequent sections cut from the tube 22 in accordance with the present invention are, however, of the character shown in Figure 3, and for this reason the reference numeral 20 has been applied to them in Figure 2.

The present apparatus is preferably mounted upon a suitable table 26. Referring for the moment to Figures 5 and 9, it will be observed that three blocks 27, 28, and 29 are secured in superposed relationship upon this table by means of the attachment bolt 30 and the aligning pins 31. The blocks 27 and 28 have superposed projecting tongues 32 and 33 provided near their ends with aligned bores 34. A slit or space 35 is formed between the tongues 32 and 33.

The block 29 has a portion arranged above the tongues 32 and 33, and in this portion there is mounted the multi-jawed chuck or collet 36. This chuck may, for example, be formed of a single tubular element, as shown, held in a suitable opening in the block 29 by means of the set screw 37. At its free end, the element 36 may be longitudinally split to provide the complementary jaws 38, as shown most clearly in Figure 10. These jaws are caused to have an inherent springiness which retains them in spread relationship. They may be moved radially into closed position by any suitable means. I have illustratively shown the outer faces of the jaws 38 arranged along a conical surface 41, and I have shown a collar 39 provided with a similar conical inner surface. The collar is screw-threaded to the threaded portion 40 of the block 29, whereby rotation of the collar will effect a relative axial movement between it and the portion 40. The opening and closing of the jaws 38 is effected by rotative movement of the collar 39. This rotative movement is controlled by means of a handle 42 projecting radially from the collar 39, as shown most clearly in Figure 5.

The chuck 36, as will be observed, is in alignment with the bores 34. Accordingly, the tube 22 may pass downwardly through the chuck and through the bores 34.

Beneath the bores 34 there is a movable abutment 43 against which the end of the tube rests.

This abutment is mounted upon a lever 44 pivoted to the table as at 45 and provided at its opposite end with an upwardly projecting pin 46 and a downwardly projecting pin 47. The spring 48, anchored to the post 49, serves normally to hold the abutment 43 in the operative position shown in Figures 5 and 9. When the lever 44 is in this position, its rear portion strikes against the post 49, thus limiting the action of the spring 48.

In the table 26, beneath the bores 34 and hence beneath the abutment 43 when the latter is in normal position, there is an opening 50 through which the sealed bodies are intended to be discharged as they are produced. Beneath the opening 50 it may be desirable to provide a discharge chute 51 which can deliver the bodies to any suitable receptacle (not shown).

On the underside of the table 26 I provide an electric motor 52. This motor may be of any desired kind or size, but very little power is needed because this motor serves only to rotate the circular saw 53. Referring for the moment to Figures 7 and 8, it will be observed that the motor is mounted upon a bracket or plate 54. This plate is secured as at 55 to a pivot pin 56 mounted in a suitable bearing 57 provided for this purpose in the table 26. The bracket 54 is adapted to swing through a slight arc around the pivot 56 as an axis.

The shaft 58 of the motor extends upwardly through the table 26, the opening 59 being suitably enlarged to allow for the swinging movement of the motor. At its upper end the shaft 58 is secured to a member 60 upon which the circular saw 53 is mounted. This saw is arranged in the plane of the space 35 (Figure 9) and projects into this space. In the normal position of the motor, the edge of the saw is out of alignment with the bores 34, but when the motor is swung around the pivot 56 the edge of the rotating saw is caused to sweep across the axis of the bores 34. It may thus be said that the saw 53, though continuously rotating, is normally inoperative as a cutting means, but becomes operative when the motor is swung through a predetermined arc.

In its normal inoperative position, the plate or bracket 54 strikes against the abutment screw 61 (see Figure 11) which is mounted in an adjustable manner on the underside of the table 26. A tension spring 62 holds the plate 54 in this normal position. When the plate is swung around the pivot 56, it strikes against the abutment screw 63 which is similarly mounted in an adjustable manner on the underside of the table 26. The movement of the plate 54 between these end positions, though slight, is sufficient to sweep the rotating saw into and out of a cutting range with respect to the axis of the bores 34.

This swinging movement of the bracket 54 may be accomplished in any desired manner. For example, a handle 64 may be secured on the motor 52 or on the bracket or plate 54, this handle projecting forwardly into an accessible position as shown in Figure 5. This handle may be grasped by the operator so that he may, by hand, swing the bracket 54 against the action of the spring 62, as indicated by dot-and-dash lines in Figure 11. I have also shown a link 65 pivoted as at 66 to the plate 54 and provided with the slotted end 67 into which the pin 47 extends. Movement of the pin 47 from the full line position of Figure 11 to the dot-and-dash position of this figure will also cause a swinging movement of the bracket

54 against the action of the spring 62, as indicated by the dot-and-dash lines.

Before describing the operation of the device, it may be pointed out that, if desired, a suitable lead shield 68 may be mounted on the block 29 above the chuck 36, as shown in Figure 5; a similar lead shield 69 may be arranged across the front of the table 26; and other protective shields, either of lead or any other material, may be provided wherever desired to shield the operator from exposure to the radioactivity within the tubes that are being treated. Also, a safety shield 70 is preferably mounted over the rotating saw.

15 The operation of the apparatus, by means of which the novel procedural steps of the present invention may be expeditiously carried out, is shown most clearly in Figures 12-14.

The jaws 38 being open, the operator first shifts 20 the handle 64 into a position which brings the saw 53 into the position shown in Figure 12. The tube 22 is then inserted downwardly through the chuck 36 and through the upper one of the bores 34 until the end 24 rests upon the saw 53. The handle 42 is then swung in the direction of 25 the arrow shown in Figure 6. This causes a tightening of the jaws 38 around the region of the tube 22 which is exposed to their action. This region, it will be observed, is spaced from the end of the tube. The squeezing action of the jaws serves to provide a pinched region on the tube 22, thereby closing the tube at this region and imparting a substantially star-shaped cross-section to it.

30 As the handle 42 swings around, it encounters 35 the pin 46. This serves not only to swing the abutment 43 out of its normal position, but serves also to move the pin 47 into the dot-and-dash position of Figure 11. (During the start of the 40 process, as just described, this movement of the pin 47 has no effect upon the saw 53, since this saw is already being held in the dot-and-dash position of Figure 11, i. e., the position shown in Figure 12, by means of the handle 64.) When the handle 42 has been swung to its extreme position, the handle 64 may be released, since the pin 47 is by this time functioning to control the swinging movements of the motor.

45 As the handle 42 is now released and swung back to the position of Figure 5, the spring 62 50 swings the motor back to its normal position, and the spring 48 swings the abutment 43 back to its normal position. At the same time, the jaws 38 are loosened, and the tube 22 drops by gravity 55 to the position shown in Figure 13. It will be observed that the tube now has a pinched region 71 which it did not have before, this pinching being the result of the action of the jaws 38 while the tube was held in the position of Figure 12.

60 It will also be observed that the parts are so arranged that when the tube strikes the abutment 43, as shown in Figure 13, the pinched region 71 is directly in the line of action of the saw 53.

65 The lever 42 is now swung again to successively 70 tighten the jaws 38, move the abutment 43 aside, and swing the saw into operation. This time, as the saw swings across the axis of the tube, it cuts transversely through the center of the pinched region 71. As a result, the end portion of the tube (designated by the reference numeral 25 in Figure 2) falls downwardly through the opening 50 into the delivery chute 51.

75 As the lever 42 is released again, and is swung

back to its normal position, the tube drops again so that it assumes the position of Figure 14. In this figure it will be observed that a new pinched region 72 has been provided, this region lying in the plane of action of the saw 53. One half of the portion 71 is now resting upon the abutment 43. As the lever 42 is again swung around and then released, the first of the blunt-ended "radium seeds" 20 is severed from the tube and allowed to drop through the opening 50.

This procedure is then repeated again and again, and each operation serves to produce and deliver another sealed body 20.

When the opposite end of the tube is reached, an oddly-shaped body, such as that shown at 25 in Figure 2, may again result, as will be understood. These oddly-shaped end bodies may be separately collected and used for special implanting purposes or they may be treated in any desired manner for recovery of the gold tubing and of the radioactive material enclosed thereby.

From the foregoing it will be understood that the handle 64 is manipulated only at the start of the operation of the apparatus, to prevent the saw 53 from cutting through an unpinched region of the tube 22.

It will thus be observed that, by the practice of my present invention, the valuable and inherently dangerous content of the tube is at all times safeguarded against escape. As each pinched region is transversely cut it produces a sealed end on each of the adjacent severed tube portions. Each of these ends is blunt and perpendicular to the tube axis. Each resultant body is the same as every other body, having the same length and shape. All these desirable results are accomplished with simplicity, speed, efficiency, and reliability.

In general, it will be understood that the details herein described and illustrated may be readily modified by those skilled in the art without departing from the spirit and scope of the invention as expressed in the appended claims. For this reason, it is intended that these details be interpreted as illustrative, and not in a limiting sense.

Having thus described my invention and illustrated its use, what I claim as new and desire to secure by Letters Patent is:

1. In an apparatus for treating a tube of the character described, operable means for pinching the tube into closed condition at a region spaced from the end of the tube, and movable means for cutting through said pinched region to provide a sealed end on each of the adjacent severed tube portions, said pinching means comprising a multi-jawed chuck through which the tube may pass, a handle connected with said jaws for opening and closing of said jaws, and means connected with the cutting means in position to be actuated by the handle to move said cutting means to a cutting position.

2. In an apparatus for treating a tube of the character described, operable means for pinching the tube into closed condition at a region spaced from the end of the tube, and movable means for cutting through said pinched region to provide a sealed end on each of the adjacent severed tube portions, said pinching means comprising a multi-jawed chuck through which the tube may pass, said cutting means comprising a rotatable saw mounted for swinging movement into and out of a position for cutting through a previously pinched region of the tube, and a common means for controlling the operation of said jaws, and means connected with the cutting means in position to be actuated by the common means to move said cutting means to a cutting position.

position to be actuated by the common controlling means to move said cutting means to a cutting position.

3. In an apparatus for treating a tube of the character described, an operable multi-jawed chuck through which the tube may pass, said jaws being adapted to pinch the engaged region of the tube into closed condition, a movable abutment arranged so as to be encountered by the end of the tube, said abutment being so spaced from the chuck that the pinched region of the tube is a predetermined distance from the end of the tube, a cutting means between the chuck and the abutment in position for cutting through a previously closed region of the tube, a handle for closing the jaws to pinch the tube at one point thereof during said cutting action at another point thereof and means actuated by said handle for moving the abutment aside.

4. In an apparatus for treating a tube of the character described, a multi-jawed chuck through which the tube may pass, said jaws being adapted, when moved radially inwardly, to pinch the engaged region of the tube into closed condition, a movable abutment arranged so as to be encountered by the end of the tube, said abutment being so spaced from the chuck that the pinched region is a predetermined distance from the end of the tube, a cutting means between the chuck and the abutment for cutting through a previously pinched region of the tube, said cutting means comprising a rotatable saw mounted for swinging movement into and out of a position for cutting through a previously pinched region of the tube, and a common means for controlling the operation of said jaws, and means connected with the cutting means in position to be actuated by the common means to move said cutting means to a cutting position, and said common means having means of connection with the abutment for moving the abutment aside as the cutting means severs the end portion of the tube.

5. In an apparatus for treating a tube of the character described, a pinching means for squeezing a region of the tube into closed condition, a cutting means for cutting through a previously sealed region of the tube, and an abutment adapted to be encountered by the tube end and so positioned with respect to the pinching means and the cutting means that one closed region of the tube at a predetermined distance from the tube end is positioned within the range of action of the cutting means while another region of the tube at a predetermined greater distance from the tube end is simultaneously positioned within the range of action of the pinching means.

6. In an apparatus for treating a tube of the character described, a pinching means for squeezing a region of the tube into closed condition, a cutting means for cutting through a previously sealed region of the tube, and an abutment adapted to be encountered by the tube end and so positioned with respect to the pinching means and the cutting means that one closed region of the tube at a predetermined distance from the tube end is positioned within the range of action of the cutting means while another region of the tube at a predetermined greater distance from the tube end is simultaneously positioned within the range of action of the pinching means, the distance between the pinching means and the cutting means being substantially equal to the distance between the cutting means and the abutment so that each endwise advancement of the tube presents to the cutting means the region

previously subjected to the action of the pinching means.

7. In an apparatus for treating a tube of the character described, an operable pinching means for squeezing a region of the tube into closed condition, a movable cutting means for cutting through a previously sealed region of the tube, an abutment adapted to be encountered by the tube end and so positioned with respect to the pinching means and the cutting means that one region of the tube at a predetermined distance from the tube end is positioned within the range of action of the cutting means while another region of the tube at a predetermined greater distance from the tube end is simultaneously positioned within the range of action of the pinching means, a common control means for actuating the pinching means, and means connected with the movable cutting means in position to be actuated by the common control means for moving the cutting means to an operative position.

8. In an apparatus for treating a tube of the character described, an operable pinching means for squeezing a region of the tube into closed condition, a movable cutting means for cutting through a previously sealed region of the tube, a movable abutment adapted to be encountered by the tube end and so positioned with respect to the pinching means and the cutting means that one region of the tube at a predetermined distance from the tube end is positioned within the range of action of the cutting means while another region of the tube at a predetermined greater distance from the tube end is simultaneously po-

5 sitioned within the range of action of the pinching means, a common control means for actuating the pinching means and for moving the abutment aside as the pinching means becomes effective, and means connected with the movable cutting means in position to be actuated by the common control means for moving said cutting means to a cutting position.

10 9. In an apparatus of the character described, the combination of elements set forth in claim 5, said pinching means comprising a multi-jawed chuck through which the tube passes, and means for moving said jaws radially.

15 10. In an apparatus of the character described, the combination of elements set forth in claim 5, said pinching means comprising a multi-jawed chuck through which the tube passes, and means for moving said jaws radially, said jaws being at least three in number and having shapes which

20 impart a substantially star-shaped cross-section to the resultant pinched region of the tube.

25 11. In an apparatus of the character described, the combination of elements set forth in claim 5, said cutting means comprising a circular saw, and means for rotating said saw.

30 12. In an apparatus of the character described, the combination of elements set forth in claim 5, said cutting means comprising a circular saw, means for rotating said saw, a swinging bracket supporting said saw, and means for swinging said bracket into and out of a position in which said rotating saw becomes effective.

FREDERICK C. WAPPLER.
